UNITED STATES PATENT OFFICE.

RUDOLPH KYSELA, OF LOS ANGELES, CALIFORNIA, ASSIGNOR OF ONE-HALF TO LEO V. STARR, OF LOS ANGELES, CALIFORNIA.

MOTOR-CONTROL MEANS AND SYSTEM AND METHOD.

Application filed October 27, 1921. Serial No. 510,774.

To all whom it may concern:

Be it known that I, RUDOLPH KYSELA, a citizen of the United States, residing at Los Angeles, in the county of Los Angeles and 5 State of California, have invented new and useful Improvements in Motor-Control Means and Systems and Methods, of which the following is a specification.

This invention relates to motor control 10 means and system and method, and has for an object the prevention of running an engine when the same commences to overheat, thus preventing excessive friction and wear of the various parts.

15 In practicing the invention I provide means which may be associated with the water jacket of an engine so that when the water reaches a certain temperature the said means will operate and in so operating will 20 stop the engine. The said means may be utilized in connection with any one of a number of systems for feeding gasoline or other fluid to the engine, and in particular the device is adapted to close the air vent 25 in a gravity tank when the water reaches a definite temperature in the water jacket surrounding the engine, or to open the air valve in the pressure system where gasoline or other fluid is forced to the intake manifold of an engine, thus preventing the gasoline from flowing to said manifold when the valve is open, or with the well-known vacuum system. In particular, the invention 30 comprises a member provided with a valve 35 which controls the air supply to any one of the systems above-mentioned and which valve is operated by thermostatic control, this control operating when the temperature of the water in the water jacket reaches a 40 certain degree.

It will be seen that a device of this character will overcome many difficulties caused by an overheated engine or motor. A motor may be overheated due to any number of 45 causes, such as impaired water circulation due to a radiator leak; impaired water circulation due to a hose leak or a faulty pump; slip timing, that is, retarding the magneto; lack of lubrication of the working parts of the engine, or in case of new pistons having been installed in the engine, the pistons being too tight and thereby causing a sticking; or a stiff motor which is common in new 50 automobiles; a slipping of the fanbelt or motor fan; improper carburetor mixture 55

causing excessive heat in the engine; and any number of difficulties. My invention effectively overcomes all this by immediately stopping the operation of the engine when the engine begins to over-heat and a driver 60 of an automobile may then examine the different parts to determine the cause of the overheating of the engine.

The invention has for further objects the provision of an improved motor control 65 means and system which will be superior in point of relative simplicity and inexpensiveness, taken in conjunction with utility, durability and general efficiency and serviceability.

With the above mentioned and other objects in view, the invention consists in the novel and useful provision, formation, construction, combination, association and inter-relation of parts, members and features, 75 as illustrated in some of its embodiments in the accompanying drawing, described in the following detailed statement and finally pointed out in the claims.

In the drawing:

Figure 1 is a fragmentary side elevation showing my improved means in connection with a water jacket of a motor, the said means in operative connection with a vacuum system;

Figure 2 is a fragmentary cross sectional view of my improved means showing the interior working parts of the same, operating in conjunction with a vacuum system;

Figure 3 is a modified form of the invention;

Figure 4 is a perspective view of one of the controlling elements used in practicing the invention; and,

Figures 5 and 6 are views showing the application of my improved means in conjunction with a gravity tank and with a pressure system, of feeding fuel liquid to a motor.

Corresponding parts in all the figures are 100 designated by the same reference characters.

Referring with particularity to the drawing, wherein I have illustrated three embodiments of the invention, one embodiment is illustrated in Figures 1 and 2 and the 105 two other embodiments in Figures 5 and 6. A designates a motor and B motor control means. In Figure 1, *a* is a vacuum tank and *b* the intake manifold of the motor. A and *c*, the water jacket of said motor. The 110

vacuum tank includes the usual two chambers 1 and 2 having divisioning walls with a float member 3 within the upper chamber 1, and a cap member 4 closing the upper chamber 1. The cap is provided with an opening permitting a pipe 5 to enter the same, which pipe leads from the gasoline tank (not shown). A second opening in said cap accommodates a valve plug 6 carrying a pipe member 7 leading to the intake passage of the manifold, and a third opening 8 in said cap, which opening ordinarily receives the air vent pipe. The opening 8 is so arranged as to allow atmospherization of the outer chamber 2 at all times, as shown by the passage 9 and for a controlled atmospherization of the chamber 1 through the medium of a valve 10. The float 3 carries the usual stem 11 to which is pivoted a lever arm 12. The system likewise includes a toggle lever 13 which is actuated by movement of the float 3 through the medium of a link 14 connecting the lever arm 12 with the toggle lever 13, which lever 13 actuates the valve members 10 and 15.

The operation of the vacuum system is as follows: A valve (not shown), is placed between the chambers 1 and 2; the suction of the pistons in the engine A on the intake stroke creates a vacuum in the chamber 1, and this vacuum closes the valve which is between the chambers 1 and 2, said valve not being shown, and also draws gasoline from the main supply tank (not shown), into the chamber 1. As the gasoline flows into this chamber the float 3 rises. When this float has reached a determined point, it operates the valves 15 and 10 so as to open the valve 10 and close the valve 15. This of course will immediately atmospherize the interior of the chamber 1 and prevents a re-drawing of further gasoline through the pipe 5 into the upper chamber 1, and likewise causing the valve leading into the lower chamber to open and through which the gasoline immediately commences to flow into the lower or emptying chamber. This lower chamber 2 is always open to the atmosphere through the medium of the opening 9.

In particular the pipe 16 leads from the chamber 2 to a carburetor *d* associated with the engine A. The means B is associated with the air vent opening 8 and acts to prevent atmospherization of both the chambers 1 and 2, and in this particular differs from the general operation of the vacuum system. As before stated, the chamber 2 is usually under atmospheric pressure in order to allow gasoline in the lower chamber to feed through the pipe 16 to the carburetor, in a perfect uninterrupted flow.

The means B comprises a housing 17 open at one end as at 18 and closed at the other end, as at 19. The interior of said housing

is screw-threaded from the open end for a distance, as shown at 20, and an annular plug 21 provided with screw threads is received within a portion of the housing 17. The annular plug 21 is likewise screw-threaded as at 22 so as to receive one end of a threaded nipple 23. The other end of said nipple is adapted to receive the screw threaded cap 24, which is adapted to receive the enlarged end 25 of a pipe 26, which pipe likewise carries a screw-threaded plug 27 adapted to be received within the opening 8. Thus when the device is assembled the enlarged end 25 is held closely to the nipple 23 so that no air will be lost through the joint. The plug 21 is provided with a conical valve seat as at 28 and a stem member 29 having a valve head 30 is adapted to contact with said valve seat during a certain operation of the means B. In particular the base or end 19 is recessed as at 31 to receive an end of the stem 29, and surrounding said stem is a compression spring 32. Said spring has one end abutting against the interior surface of the end 19, and the other end against a pin 33 passing through the stem 29 and normally urging the stem outwardly so that the valve head 30 will not engage the seat 28. Likewise surrounding and carried upon the stem 29 is a thermostat *e* which includes two members 34 and 34^a identical in construction and each provided with angularly directed end portions 35 and 36 having openings 37 therein adapted to receive the stem 29. The thermostat *e* comprises two metals 38 and 39, 38 being brass and 39 being iron, or they may be of any other metals having unequal expansion due to temperature change. The housing 17 is provided with an opening 40 and the stem 29 is relieved as at 41 so as to allow air to enter the opening 40 and through a passage 42, and thence into the vacuum tank. In the embodiment shown in Figures 1 and 2 the housing 17 carries a solid lug 43 provided with screw threads 44. The water jacket *c* is likewise bored and tapped, and the member 44 received within said tapped bore, as shown at 45. The thermostatic members 34 and 34^a have one end bearing against the plug 21 and the other bearing against the pin 33. Obviously, if the temperature of the water reaches a given degree the heat will be conducted through the solid lug 43 to the housing 17, and the said heat will thus affect the thermostat *e* tending to expand or twist the ends 35 and 36 of the members 34 and 34^a, and this will close the valve so that air cannot enter through the opening 8. Of course this closing is done under the resistance expended by the spring member 32. If the air opening 8 were closed the vacuum system would cease to function and as a result the motor would stop running, due to lack

130

of fuel feeding to the carburetor *d*. The point at which the means *B* will operate depends to a certain extent upon the compression of the spring *32*, as the spring *32* 5 may exert so much pressure as to prevent the valve from closing. This compression may be regulated by turning the plug *21* and then locking the plug at the desired point by means of a screw *46* carried by 10 the housing and having a part engaging the plug.

It will be a simple matter to calibrate the device *B* by the adjustment just described. In Figure 3 in place of using the solid 15 lug *43* the housing *17* is provided with tapered threads *47* and the water jacket is provided with a tap bore adapted to receive the part *47*. In this case the housing *17* will be received within the water jacket 20 and will be acted directly upon by the water flowing therein. The operation, however, would be the same.

Referring to Figure 6 I have illustrated in diagrammatic form the use of my invention 25 in conjunction with the well-known gravity feed. In this connection it may be said that a tank *D* adapted to hold gasoline or other fluid ordinarily has an air hole so that gasoline will flow therefrom to the intake manifold. In utilizing my invention I have a pipe *48* joined to the tank *D* at the air hole opening in such a manner as to completely seal the parts surrounding the air hole opening; said pipe *48* in turn leading 30 to the cap nut *24*. As before stated, the means *B* may either have the lug *43* or the part *47* having connection with the water jacket *c* of the engine. Then, if the water reaches a certain temperature within the water jacket the valve in the means *B* will 35 close and seal the opening in the tank *D* and prevent flow of gasoline therefrom to the intake manifold.

In Figure 5 I have illustrated a pressure 40 system in which the gasoline within a tank *E* is maintained under pressure. The means *B* must be modified to operate with said pressure system and the modified form is shown as *B'*, and in which a pipe *49* leads to 45 an opening in the tank *E* and in turn to the cap nut *24*. The internal mechanism of the means *B'* is reversed; that is to say, the spring *32* is so placed as to at all times keep the head *30* seated upon the valve seat *28*. The thermostat *e* is reversed in its position 50 so that when it expands it forces the valve head *30* from the seat *28* and in so doing will allow the tank *E* to be under atmospheric pressure, whereupon the system will become 55 inoperative. This mere reversal of parts in the means *B'* does not differ essentially from the means *B*, the principle of operation being the same.

It is perhaps unnecessary to state that the 60 means *B* may be connected with and oper-

ate in conjunction with the filler plug of the vacuum system in place of the air vent opening. The operation of course would be the same, as when the means *B* operated it would bleed the vacuum. I do not wish to confine 70 this invention to a means which must be associated with the water jacket, but wish it understood that the said means may be attached at any point of the engine where it would be subjected to temperature 75 changes, due to operation of said engine. In other words, the device operates on the variations of temperature, which variations of temperature when the said device is used with a vacuum system, causes an atmospheric variation in said vacuum system to render the said vacuum system either operative or inoperative.

An invention of this character would be adaptable for many uses other than for feeding gasoline or oil for automobile, and I do not wish to be understood as confining it to an automobile, as it may be used in aeroplanes, tractors, and in fact, anywhere that an internal combustion engine is utilized.

It is obvious that many changes and variations and modifications may be made in departure from the particular description and showing of the accompanying drawing, in adapting the invention to varying conditions and requirements of use and service, without departing from the true spirit of the invention.

Having thus disclosed my invention, I claim and desire to secure by Letters Patent:

1. The combination, with a vacuum system for supplying liquid fuel to internal combustion motors, of means associated with said motor and said system for cutting off air supply to the vacuum system and thus preventing fuel supply to said motor if the motor starts to overheat.

2. The combination, with a vacuum system for supplying liquid fuel to an internal combustion motor, of means associated with said vacuum system and operating responsive to temperature changes due to operation of said motor, and whereby said means will shut off air supply to said vacuum system and prevent the feeding of liquid fuel to said motor at a determined temperature of said motor.

3. The combination with an internal combustion engine and a vacuum system for feeding fuel thereto, of means associated with said engine and adapted to operate when the engine starts to overheat to stop operation of the engine, said means preventing atmospherizing of said vacuum system, thus preventing flow of fuel from said vacuum system when the motor overheats.

4. The combination with a water jacket of an internal combustion engine and a vacuum system for supplying fuel to said engine, of means carried by the water jacket

and adapted to be influenced by the heat of the water carried within said water jacket, said means preventing atmospherizing of said vacuum system to render the same inoperative when the water within said water jacket reaches a determined temperature.

5. The combination with a water jacket of an internal combustion engine and a vacuum system for supplying fuel to said engine, of means carried by the water jacket

10 and adapted to be influenced by the heat of the water carried within said water jacket, said means preventing atmospherizing said vacuum system so as to render the same inoperative when the water within said water jacket reaches a determined temperature; said means comprising a thermostat adapted to be actuated by heat changes of the water supply within the said water jacket, said

15 20 thermostat controlling an air valve associated with the vacuum system.

6. The combination with a water jacket of an internal combustion engine and a vacuum system for supplying fuel to said

25 engine, of means carried by the water jacket and adapted to be influenced by the heat of the water carried within said water jacket, said means preventing atmospherizing said vacuum system so as to render the same inoperative when the water within said water jacket reaches a determined temperature; said means comprising a casing, a valve within said casing, means for normally maintaining said valve open, and means for

30 35 closing said valve when the temperature of the water within the jacket reaches a determined point.

7. The combination with a water jacket of an internal combustion engine and a vacuum system for supplying fuel to said engine, of means carried by the water jacket

40 and adapted to be influenced by the heat of the water carried within said water jacket, said means preventing atmospherizing said vacuum system so as to render the same inoperative when the water within said water jacket reaches a determined temperature; said means comprising a casing, a valve within said casing, means for normally

45 50 maintaining said valve open, and means for closing said valve when the temperature of

the water within the jacket reaches a determined point; there being a conduit joined with said casing and with the air vent opening of the vacuum system, and the said casing being provided with an air opening on one side of said valve, whereby when the valve is open air is allowed to pass within the vacuum system and when the valve is closed air is prevented from entering the

55

water jacket reaches a determined temperature; said means comprising a casing, a valve within said casing, means for normally maintaining said valve open, and means for closing said valve when the temperature of the water within the jacket reaches a determined point; there being a conduit joined with said casing and with the air vent opening of the vacuum system, and the said casing being provided with an air opening therein on one side of said valve, whereby when the valve is open air is allowed to pass within the vacuum system and when the valve is closed, air is prevented from entering the vacuum system; means being provided for adjusting the first named means whereby it will operate at a determined temperature.

9. In combination, an engine, a vacuum system for feeding fuel to run said engine, and means operating responsive to temperature changes of said engine to prevent atmospherizing said vacuum system at a determined temperature of said engine.

In testimony whereof, I have signed my name to this specification in the presence of two subscribing witnesses.

RUDOLPH KYSELA.
